UNITED STATES PATENT OFFICE.

RICHARD MOBLEY, OF ST. LOUIS, MISSOURI.

CAR-DOOR.

SPECIFICATION forming part of Letters Patent No. 760,902, dated May 24, 1904.

Application filed June 23, 1903. Serial No. 162,793. (No model.)

To all whom it may concern:

Be it known that I, RICHARD MOBLEY, a citizen of the United States, residing at St. Louis, in the State of Missouri, have invented new 5 and useful Improvements in Car-Doors, of which the following is a specification.

This invention relates to car-doors, and particularly to that class of such doors known as "flush" doors, which seat in door-openings 10 formed in the sides of the cars flush with the outer surface of the latter; and it has for its object to improve and simplify the construction and facilitate and render more efficient the operation of such doors.

15 To these ends my invention consists in the features and in the construction, combination, and arrangement of parts hereinafter described, and particularly pointed out in the claims following the description, reference being had to the accompanying drawings, forming a part of this specification, wherein—

Figure 1 is a view in front elevation, showing the door seated in the door-opening and locked. Fig. 2 is a vertical sectional view 25 taken on the line 2 2 of Fig. 1. Fig. 3 is a view in front elevation showing the door raised and swung out from the door-opening. Fig. 4 is a vertical sectional view taken on the line 4 4 of Fig. 3. Fig. 5 is a detail view 30 of the door-operating mechanism removed from the car and door. Fig. 6 is a detail sectional view illustrating the preferred manner of mounting the wheels carried by the hangers that support the door, and Fig. 7 is a detail 35 view of a modification.

Referring to the drawings, the numeral 1 indicates the side of the car, and 2 a door-opening formed therein, the top and bottom or sill of the car being inwardly beveled, as shown 40 at 3 and 4.

The numeral 5 indicates the door which is beveled at top and bottom to correspond to and fit the bevels 3 and 4, so that when the door is closed tightly it will seat flush in the 45 door-opening with the outer side of the car.

Attached to the side of the car above the door-opening and extending to one side thereof is a trough-shaped metallic track 6, and fixed above said track is an inverted-trough-shaped hood 7, provided with a depending 50

flange 8, which overhangs the outer side of the track. Said hood serves to prevent rain, snow, dirt, and the like from gaining access to the track. Attached to the upper portion of the outer side of the door are two brackets 55 9, each being substantially U-shaped and provided at its upper ends with bearings 10, the lower end of each of the brackets being bent at right angles to form a flange 11, in which is formed an aperture 12. Passing loosely 60 through each of said apertures is the lower end of a hanger 13, the upper end of which is bent into substantially inverted-U shape, as indicated at 14, to overhang the track 6. Journaled in the upper inverted-U-shaped 65 portion of the hangers are axles 15 on which are mounted wheels 16, that are adapted to travel on the track. As before stated, the lower ends of the hangers pass loosely through the apertures 12 in the brackets 9, and the 70 lower extremities of said hangers are provided with laterally-projecting lugs 17, for a purpose hereinafter explained.

Journaled in the bearings 10 of the brackets is a rock-shaft 18, said rock-shaft between 75 the two members of each bracket being bent to form a crank 19, said cranks being rotatably mounted in bearings 20, formed on or attached to the hangers. The rock-shaft 18 midway between its ends is bent to form a 80 crank 21, said crank being set at a slight angle relatively to the cranks 19, before referred to.

Secured centrally to the upper portion of the door is a substantially U-shaped bracket 22, the two members of which are provided at 85 their upper ends with bearings 23, which embrace the rock-shaft on each side of the crank 21. Loosely attached to the central crank 21 is the upper end of a vertical rod 24, which intermediate its ends passes loosely through 90 a guide 25, attached centrally to the door. Attached centrally to the lower portion of the door is an oscillatory lever 26, said lever being pivoted midway between its ends on a pivot pin or stud 27 fixed to the door. 95 The opposite ends of said lever are provided with laterally-projecting loops 26^a, forming handholds, and a perforation 28 is formed in said lever eccentrically to or on one side of the fulcrum of the lever, and the lower 100

end of the rod 24 is bent at an angle, as at 29, and said angular portion is loosely fitted in said aperture.

Attached centrally to the door-sill beneath the door-opening is a bracket 30, provided at its upper end with a bearing or bearings 31 in which is rotatably mounted a rod 32, the end of which is bent at a right angle to form what I term a "sealing-pin" 33, said pin being provided with an aperture 34. One side of the bracket 30 is provided with a laterally-projecting flange 35, provided with an aperture 36.

Fixed to the door-sill at each side of the door-opening is a bracket-lug 37, provided at its outer portion with a vertically-projecting flange 38, said bracket-lugs operating to prevent the door from swinging too far outwardly when the door is opened. When the door is closed tightly, the lower edge thereof drops behind the inner sides of the bracket-lugs and holds the lower edge of the door tightly in place. A similar bracket-lug 39 is fixed to the exterior of the car to one side of the door-opening, and stop-lugs 40 and 41 are fixed to the side of the car to limit the lateral movement of the door in either direction.

The operation of my improved door is as follows: To close the door, it is moved along the track opposite the door-opening. Then by giving the lever 26 a slight turn, so as to oscillate the rock-shaft 18 sufficiently to throw the cranks 19 out of a vertical plane, the weight of the door will cause the latter to drop, and in dropping the cranks 19 are turned so as to cause them to throw the upper edge of the door to its seat in the door-opening. As the door lowers itself into place its lower edge drops behind the bracket-lugs 37, and the lower edge of the door is thereby firmly held in place. The upper edge of the door is held in place by the cranks 19, which as the door drops into place push the upper edge of the door to its seat. The door will now be held flush with the exterior surface of the car. As the door automatically drops to its seat in the door-opening the lever 26 through the medium of the rod 24 and central crank 21 is turned to a vertical position, and one of the loops 26^a is thereby caused to pass over the sealing-pin 33, the latter having first been turned to a vertical position. The sealing-pin is then turned down vertically, so that its aperture 34 will be in alinement with the aperture 36 in the flange of the bracket 30, after which a wire may be run through said apertures and its ends secured by a lead seal in the usual manner, thus locking the door in place and preventing its being turned without defacing or destroying the seal. To open the door, the sealing-pin is turned up to a vertical position, and the operator then grasps the two loops 26^a on the lever 26 and turns said lever to a horizontal position. As said lever

is turned to such position, the vertical rod 24 being connected eccentrically to said lever, said rod is turned downwardly, thereby drawing down the central crank 21 of the rock-shaft and turning the latter in its bearings, so as to throw the cranks 19 into a vertical position. As said cranks assume such vertical position they exert a lifting action on the door, raising the lower end of the door from behind the bracket-lugs 37 and at the same time raising the upper edge of the door and throwing it away from the door-opening. When the cranks 19 have assumed a perfectly vertical plane, the weight of the door will hold them in such position and will hold the door thrown outwardly away from the door-opening. The door may now be slid to one side of the door-opening upon its track entirely clear of said door-opening, and when in this position the weight of the door causes it to hang closely against the side of the car and prevents the door from moving, owing to the vibrations of the car. As before stated, the weight of the door assists in closing it and holding it shut and also holds it against movement or from jerking back and forth on the track when open, due to the motion of the car. The lower ends of the hangers 11 pass loosely through the apertures 12 in the brackets 9 and prevent the lower ends of the hangers and the door from swinging or moving away one from the other, and the lugs 17 on the lower ends of the hangers are provided for the purpose of catching the door and preventing it from dropping from place in case of breakage.

By means of the arrangement shown and described but slight force is necessary to operate the parts to raise the door from its seat in opening said door, and, as before stated, the weight of the door itself materially assists in causing the door to seat itself flush in the door-opening.

In mounting the wheels 16 in the hangers 13 the axles 15, before referred to, preferably consist of bolts, which pass through the opposite sides of the hangers 14, as most clearly shown in Fig. 6 of the drawings. Arranged on the bolts 15 are sleeves 15^a, and the wheels 16 are rotatably mounted on said sleeves. After the parts have been assembled the bolts are tightly drawn up into place, contracting the sides of the hangers 14 and causing them to clamp the sleeves between them, so that said sleeves will be held against rotation. The purpose of such an arrangement is to take the wear of the wheels from off the bolts or axles and to enable the parts to be cast very hard, so they will be rendered durable. If desired, shoulders may be formed on the ends of the sleeves, which will impinge against the sides of the hangers and aid in preventing the sleeves from rotating.

In Fig. 7 I have illustrated a modified form of mechanism for operating the rod 24 and for

locking and sealing the parts. Referring to said figure the numeral 42 indicates the bail-shaped lever provided centrally at its upper end with a crank portion 43. The rod 24 is provided near its lower end with an eye 44, in which is loosely journaled the crank portion 43 of the lever, and the lower extremities of said rod are provided with a hook 45. The numeral 46 indicates a plate having formed thereon a vertical cylinder-housing in which is movably fitted the bolt 47. Said housing is slotted on its opposite sides, as at 48, and formed on the upper end of the bolt are lateral projections 49, which pass through said slot, furnishing ready means for raising the bolt. The upper end of the plate 46 is provided with a loop 50, and formed on said plate a slight distance below the housing is a perforated lug 51, the perforation in said lug being in alignment with the bolt. The lower end of the said plate is perforated, as at 52, and through said perforation extends a staple or U-shaped bolt 53, on which is fixed a washer-plate 54. Said bolt or staple is fixed in the side of the car centrally below the door-sill, as shown, and holds the plate 46 in place. The lower hooked end of the rod 24 engages the loop formed on the upper end of the plate. The operation of this portion of the device is as follows: When the lever is raised into an upright position, it lowers the rod 24 and rocks the shaft 18, so as to open the door, and conversely, when said lever is turned down it presses the door to its seat and holds it securely thereto. The lower end of the bail-shaped lever when in its lowered position rests between the housing and the perforated lug beneath the latter, and the bolt falls by gravity and its lower end passes through the perforated lug, thereby locking the lever in place. The lower end of the bolt is perforated, as shown, and the parts may be readily sealed by passing a wire through the perforation in the lower end of the bolt and through the staple and then securing the ends of the wire together by lead seal in the usual well-known manner. The upper end of the bail-shaped lever is journaled in clips 55, which are attached to the lower portion of the door on opposite sides of the crank portion of said lever.

Having described my invention, what I claim is—

1. The combination with a car having a door-opening therein and a sliding door for said opening, of a track attached to the side of the car and extending over the door-opening, hangers arranged to travel on the track and each provided with straight pendent shanks, brackets attached to the upper portion of the door and straddling and vertically movable on said pendent straight portions of the hangers, mechanism connected with the door and with said hangers arranged to raise the door and simultaneously to swing it outward from the

door-opening, and means for limiting the sliding movement of the brackets on the hangers, substantially as described.

2. The combination with a car having a door-opening therein and a door for said opening, of a track attached to the side of the car and extending over the door-opening, hangers arranged to travel on the track, brackets attached to the upper portion of the door and slidably arranged on the hangers, a rock-shaft journaled in the brackets and provided with cranks journaled in the hangers and means for turning said rock-shaft to raise the door and swing it outward from the door-opening substantially as described.

3. The combination with a car having a door-opening therein and a door for said opening, of a track attached to the side of the car and extending over the door-opening, hangers arranged to travel on the track, and brackets attached to the upper portion of the door and slidably arranged on the hangers, a rock-shaft journaled in the brackets and provided with cranks journaled in the hangers and with an auxiliary crank, a rod connected at its upper end to the auxiliary crank and a hand-lever pivoted intermediate its ends to the door and connected at one end to the lower end of said rods, substantially as and for the purpose specified.

4. The combination with a car having a door-opening therein and a door for said opening, of a track attached to the side of the car extending over the door-opening, brackets attached to the door and provided with laterally-projecting apertured flanges, hangers arranged to travel on the track, the lower ends of said hangers passing loosely through said apertured flanges whereby the door may be raised and lowered independently of the hangers and swung in and out of the door-opening, substantially as described.

5. The combination with a car having a door-opening therein and a door for said opening, of a track attached to the side of the car and extending over the door-opening, brackets attached to the door and provided with laterally-projecting apertured flanges, hangers arranged to travel on the track, the lower ends of said hangers passing loosely through said apertured flanges, the lower ends of said hangers being provided with laterally-projecting lugs, substantially as described and for the purpose specified.

6. The combination with a car having a door-opening therein and a door for said opening, of a track attached to the side of the car and extending over the door-opening, brackets attached to the door and provided with laterally-projecting apertured flanges, hangers arranged to travel on the track, the lower ends of said hangers passing loosely through said apertured flanges, and crank connections between said hangers and brackets whereby the door may be raised and lowered independently

of the hangers and swung in and out of the door-opening, substantially as described.

7. The combination with a car having a door-opening therein, a door for said opening, 5 a track attached to the side of the car and extending over the door-opening, brackets attached to the door and provided with laterally-projecting apertured flanges, hangers arranged to travel on the track, the lower ends 10 of said hangers passing loosely through said apertured flanges, crank connections between said hangers and brackets, and means for turning said cranks whereby the door may be raised and lowered independently of the hangers and swung in and out of the door-opening, 15 substantially as described.

8. The combination with a car having a door-opening therein, and a door for said opening, of a track attached to the side of the car 20 and extending over the door-opening, brackets attached to the door and provided with laterally-projecting apertured flanges at their lower ends, hangers arranged to travel on the track, the lower ends of said hangers passing 25 loosely through said apertured flanges, a rock-shaft journaled in said brackets and having cranked portions journaled in bearings on the hangers, and means for turning the rock-shaft to raise and lower the door and swing it in 30 and out of the door-opening, substantially as described.

9. The combination with a car having a door-opening therein and a door for said opening, of a track attached to the side of the car 35 and extending over the door-opening, brackets attached to the door and provided with laterally-projecting apertured flanges at their lower ends, hangers arranged to travel on the track, the lower ends of said hangers passing 40 loosely through said apertured flanges, a rock-shaft journaled in said brackets and having cranked portions journaled in bearings on the hangers, a crank on the rock-shaft intermediate the first-named cranks, a vertical rod 45 loosely connected at its upper end to said central crank, and an oscillatory lever pivotally mounted intermediate its ends on the lower portion of the door, the lower end of said rod being loosely connected eccentrically to said 50 lever, substantially as described.

10. The combination with a car having a door-opening therein and a door for said opening, of a track attached to the side of the car and extending over the door-opening, brackets 55 attached to the door and provided with laterally-projecting apertured flanges at their lower ends, hangers arranged to travel on the track, the lower ends of said hangers passing loosely through said apertured flanges, a rock- 60 shaft journaled in said brackets and having crank portions journaled in bearings on the hangers, a crank on the rock-shaft intermediate the first-named cranks, a vertical rod loosely connected at its upper end to said central crank, and an oscillatory lever pivotally 65

mounted intermediate its ends on the lower portion of the door, said lever being provided at its opposite ends with loops forming hand-holds, the lower end of said rod being loosely connected eccentrically to said lever, substantially as described. 70

11. In combination with a car having a door-opening therein and a door for said opening, of a track attached to the side of the car and extending over the door-opening, brackets attached to the door and provided with laterally-projecting apertured flanges at their lower ends, hangers arranged to travel on the track, the lower ends of said hangers passing loosely through said apertured flanges, a rock-shaft 80 journaled in said brackets and having cranked portions journaled in bearings on the hangers, a crank on the rock-shaft intermediate the first-named crank, a vertical rod loosely connected at its upper end to said central crank, 85 an oscillatory lever pivotally mounted intermediate its ends on the lower portion of the door, said lever being provided at its opposite ends with laterally-projecting loops, and a cranked sealing-pin journaled in a bracket 90 fixed below the door-opening and adapted to be turned to a vertical position to permit one of said loops to pass thereover and downwardly into a reverse position to lock said lever against movement, substantially as described. 95

12. In combination with a car having a door-opening therein and a door for said opening, of a track attached to the side of the car and extending over the door-opening, brackets attached to the door and provided with laterally-projecting apertured flanges at their lower ends, hangers arranged to travel on the track, the lower ends of said hangers passing loosely through said apertured cranked portions journaled in bearings on the hangers, a crank on the rock-shaft intermediate the first-named crank, a vertical rod loosely connected at its upper end to said central crank, an oscillatory lever pivotally mounted intermediate its ends on the lower portion of the door, said lever being provided at its opposite ends with laterally-projecting loops, an apertured cranked sealing-pin journaled in a bracket fixed below the door-opening and adapted to be turned up to a vertical position to permit one of said loops to pass thereover and downwardly into a reverse position to lock said lever against movement, and a laterally-projecting apertured flange on said last-named bracket arranged to register with the apertured portion of the sealing-pin when the latter is turned downward into locking position for the purpose specified. 110 115 120

13. The combination with a car having a door-opening therein and a door for said opening, of a track attached to the side of the car and extending over the door-opening, brackets attached to the door and provided with laterally-projecting apertured flanges at their lower ends, hangers arranged to travel on the track, 125 130

the lower ends of said hangers passing loosely through said apertured flanges, a rock-shaft journaled in said brackets and having crank portions journaled in the bearings of the hangers, a crank on the rock-shaft intermediate the first-named crank, a vertical rod loosely connected at its upper end to said central crank, an oscillatory lever pivotally mounted on the lower portion of the door and connected to the lower end of the said rod for raising

and lowering the latter, and means for locking the said lever against movement when the door is closed, substantially as described.

In testimony whereof I have hereunto set my hand in presence of two subscribing witnesses.

RICHARD MOBLEY.
